TUBE PUNCTURE TESTING MACHINE

Volney M. Crothers, Lambert, Miss.

Application September 19, 1952, Serial No. 310,431

1 Claim. (Cl. 73—49)

1 This invention relates to devices particularly adapted for holding inner tubes of motor vehicle tires under water in a tub or container, and in particular a disc having radially disposed tube engaging arms slidably mounted thereon positioned on a post extended upwardly from a tub or container with a latch for retaining the disc in position for holding a tube below the surface of water in the container.

The purpose of this invention is to provide means for holding an inner tube of a motor vehicle tire submerged to facilitate locating a leak in the tube.

Various types of devices have been provided for holding inner tubes of motor vehicle tires, however, it is difficult to retain the entire tube submerged while spotting a leak in the tube. With this thought in mind this invention contemplates a container having a vertically disposed post therein with a slider having a disc with radially positioned arms on the post, and in which the slider is provided with a latch whereby a tube positioned over the device with the arms contracted may be engaged by the arms with the arms in extended positions and forced downwardly below water in the container.

The object of this invention is, therefore, to provide means for forming a tube holding device whereby an entire tube may readily be forced downwardly below the surface of water in a container and in which means is provided for retaining the tube submerged until a leak therein is located.

Another object of the invention is to provide a tube submerging device upon which a tube may readily be positioned.

A further object of the invention is to provide a motor vehicle tire inner tube submerging device which is of a simple and economical construction.

With these and other objects and advantages in view the invention embodies a substantially cylindrical container having a vertically disposed post extended upward from the center thereof with a slider having spaced horizontally disposed discs mounted thereon and with one of said discs provided with adjustable radially disposed arms whereby with the slider actuated by handles extended from the upper end a tube may readily be forced downward by the arms and retained in a submerged position by a latch in one of the handles.

Other features and advantages of the invention will appear from the following description taken in connection with the drawings, wherein:

2

Figure 1 is a vertical section through the inner tube submerging device showing a tube held below the surface of water in a container thereof by arms on a disc on the lower end of a slider.

Figure 2 is a sectional plan through the upper part of the device taken on line 2—2 of Figure 1.

Figure 3 is a side elevational view of the device with part of the container broken away showing the slider in an upper position whereby the slider is positioned above a tube on water in the container.

Figure 4 is a detail illustrating the center post of the device.

Figure 5 is a sectional plan taken on line 5—5 of Figure 1 showing the base plate for retaining the post in the center of the bottom of the container.

Figure 6 is a longitudinal section through one of the handles of the slider illustrating a latch 20 slidably mounted in the handle.

Figure 7 is a detail showing a plan view of one side of the disc at the lower end of the slider.

Figure 8 is a cross section through the socket for holding the arms illustrated in Figure 7 being taken on line 8—8 of Figure 7.

Referring now to the drawings wherein like reference characters denote corresponding parts the improved inner tube submerging device of this invention includes a vertically disposed post 10 mounted on a base plate 11 in a container 12 with a slider having handles 13 and 14 extended from a tube 15 slidably mounted on the post 10 and having a disc 16 at the lower end of the tube which supports a lower disc or body member 17 on which radially disposed arms 18 are slidably mounted in sockets 19, and rods 20 are rigidly connected to upper and lower discs.

The post 10, which is shown in detail in Figure 4, is provided with a threaded stud 21, at the lower end and the upper part of the tube is provided with spaced openings 22 that are positioned to receive a bolt 23 of a latch positioned in the handle 14.

The stud 21 is threaded into a boss 24 on the base plate 11 and the plate 11 is secured to a bottom 25 of a container 12 with rivets 26.

The tube 15 is slidably mounted on the tubular post 10 and the upper disc 16 is secured to the lower end of the tube 15, preferably by welding, as indicated at the point 27. The lower disc 17 is also provided with a tubular sleeve, as indicated by the numeral 28, which is slidably mounted on the post 10. The lower disc is provided with arm retaining sockets such as the sockets 19, which are radially positioned where-

by arms 18, having arcuate flanges 29 on the outer ends are adjustably mounted on the disc. The sockets 19 are secured to the upper surface of the disc with rivets 30 and each socket is provided with a longitudinally disposed slot 31 in which pins 32 in the inner ends of the arms 18 are positioned whereby the pins provide means for limiting outward movement of the arms. By this means the arms are moved inwardly to facilitate placing an inner tube, as indicated by the numeral 33, over the lower disc and after the tube is in position, as shown in Figure 3, the arms are drawn outwardly whereby the flanges 29 extend over the outer edge of the tube.

The handles 13 and 14 are secured to the upper end of the tube 15, preferably by welding, as illustrated in Figure 1, and the handles are supported with gusset plates 34 and 35.

The handle 14 in which the latch bolt 23 is positioned is provided with a slot 36 through which a finger 37 of the bolt 23 extends and the outer end of the handle is provided with a threaded cap 38 for retaining the spring 39 in the handle. One end of the spring 39 bears against a collar 40 on the latch bolt 23 whereby the bolt is urged inwardly with the inner end extended through an opening 22 of the post 10 when the bolt is released. The bolt is drawn outwardly by the finger 37 to adjust the position of the slider and disc.

With the parts arranged in this manner the container 12 is partly filled with water and with the arms 18 drawn inwardly in the sockets a tube, such as the tube 33 is placed over the upper end of the slider and positioned on the water, as shown in Figure 3. With the tube in position the arms 18 are drawn outwardly and the slider moved downwardly by the handles 13 and 14 whereby the tube is forced below the surface of the water, as shown in Figure 1, and with the slider in this position the latch bolt 23 is released whereby the end of the bolt extends into one of the openings 22 of the post and retains the slider with the tube submerged until a leak in the tube is located. The tube is readily removed by releasing the latch and withdrawing the arms 18.

It will be understood that modifications, within

the scope of the appended claim, may be made into the design and arrangement of the parts without departing from the spirit of the invention.

5 What is claimed is:

In a tube testing device, a container adapted to hold a quantity of water, a base plate positioned in said container and secured to the bottom thereof, said base plate being provided with a threaded socket, a vertically disposed post extending upwardly from said base plate, a tube slidably mounted on said post, a disc secured to the lower end of said tube, a plurality of converging rods each having their upper ends secured to said disc, a body member positioned below said disc and supported by the lower ends of said rods, a plurality of sockets secured to the upper surface of said body member, each of said sockets being provided with a longitudinally extending slot, an arm slidably mounted in each of said sockets, a threaded stud depending from the lower end of said post for engaging the threaded socket in said base plate, the upper portion of said tube and post being provided with a plurality of spaced openings, a first and second handle extending from said tube and secured thereto, a latch slidably mounted in said first handle and including a bolt mounted for movement into and out of engagement with the openings in said post, a tubular sleeve secured to said body member for engaging said post, an arcuate flange secured to the outer end of each of said arms and adapted to be engaged by an inner tube, said first handle being provided with a slot, a finger secured to said bolt and slidably extending through said last named slot, a cap mounted on the outer end of said handle, a collar mounted on said bolt, and a coil spring positioned in said first handle and interposed between said collar and said cap.
